WALKING BEAM

Filed April 2, 1931

Lee J. Black Inventor

By *Frederick J. Stein*, Attorney

UNITED STATES PATENT OFFICE

LEE J. BLACK, OF BEAUMONT, TEXAS

WALKING BEAM

Application filed April 2, 1931. Serial No. 527,272.

This invention relates to walking beams used for pumping wells or for other like purposes and particularly to the provision of means whereby the end of the walking beam 5 may be swung to clear space for the operation of tackle blocks in pulling rods or tubing, or replacing them and the like operations.

One of the objects of the present invention is to provide means whereby one end of the 10 walking beam may be swung out of the way, as above stated, which will remove the necessity of taking down the pitmen connected thereto and cocking the beam to an upwardly inclined position as is normally done.

15 A further object is to provide a walking beam with an extension or section hinged to one end of the walking beam and forming a part thereof and particularly to provide a nose or extension which is hinged to the walking beam for alternate swinging movement, but which may be locked in a position of alignment with the walking beam.

Other objects have to do with the details of construction and arrangements of parts as 25 will be more fully hereinafter described.

My invention is illustrated in the accompanying drawing, wherein:—

Figure 1 is a side elevation of a portion of a walking beam and the Samson post supporting it and showing my improvement applied thereto;

Figure 2 is a fragmentary top plan view of one end of the walking beam;

Figure 3 is a section on the line 3—3 of 35 Figure 1.

Referring to this drawing, 10 designates the usual Samson post, and 11 the usual walking beam pivotally mounted upon the Samson post by bearings 12 and trunnions 13. 40 The rear end of the beam, which is not shown in Figure 1, is connected, of course, by the usual pitmen to the usual gear reduction unit crank arm and motor or any other suitable mechanism whereby the walking beam may be 45 vertically oscillated. Inasmuch, as these parts have nothing to do with my invention I have not illustrated them.

The forward end of the walking beam is 50 provided with a section 14 constituting an extension of the walking beam and hinged to the

body of the walking beam by a vertical pintle 15. This pintle passes through eyes formed upon a hinge section 16 (see Figure 3) which is formed to embrace the web of the walking beam, which beam is I-shaped in cross section. This portion 16 being riveted to the web as shown in Figure 3. The upper and lower ends of the hinge portion 16 are flanged at 17 to fit the upper and lower flanges of the eye beam constituting the walking beam and are riveted thereto. The hinge section 16 is formed with one or more eyes 18 and is also provided with the outwardly extending lateral flange 19.

The nose or extension 14 is formed with 65 coating eyes 20 and the pintle 15 passes vertically downward through the eyes 18 and 20 to thus hingedly connect the section 14 to the body 11. The section 14 is also I-shaped in cross section and is provided at its rear end 70 with the laterally projecting flange 21 which when the section 14 is in alignment with the body 11 abuts against the flange 19.

Bolts 22 pass through these abutting portions 19 and 21 thus holding these flanges 19 and 21 in engagement with each other and hold the section 14 in positive alignment with the section 11. The outer end of the section 14 is bifurcated at 23, as shown in Figure 2, for pivotal engagement with the usual hanger 80 24 connected to the rods in the well.

It will be seen that under ordinary circumstances and when it is necessary to use the walking beam, that the section 14 may be 85 swung into alignment with the body 11 and held rigidly in this position, but that when it is desirable to clear the space immediately beneath the forward end of the walking beam for the operation of the tackle blocks, in pulling rods or tubing or replacing them in the hole, then the bolts 22 are removed and the section 14 is swung around to the dotted line position in Figure 2, thus providing a clearance for the hoisting of the tubing and rods. When the tubing and rods have been replaced 90 in the well, the section 14 is swung back to its operating position, replacing the bolts and attaching the hanger 24 to the polish rod in the well and the mechanism is again ready for 95 pumping.

It will be seen that this structure does away with the necessity of taking down the pitmen which connect to the rear end of the walking beam and cocking the beam, and it also removes the necessity of handling any counter-weights which are usually applied to the walking beam.

While I have illustrated the use of bolts 22 for the purpose of holding the section 14 in alignment with the section 11, any other 10 suitable locking means might be provided for this purpose and I do not wish to be limited to the bolts nor to the details of construction except and in so far as these are stated in the 15 claims.

15. What I claim is:—

1. A walking beam and an extension hinged to said walking beam for lateral movement into or out of an operative position of alignment with the body of the walking beam, and means for locking the extension in this position of alignment.

2. A walking beam having an extension at one end thereof hinged to the body of the beam for lateral swinging movement relative to the body of the beam, and means for locking the extension in alignment with the body of the beam.

3. A walking beam having an extension hinged to the body of the beam for lateral movement, the beam having coacting abutments on the extremity of the beam body and the inner extremity of the section limiting the movement of the extension laterally in 35 one direction into a position where it is in alignment with the body of the beam, and means for locking said abutments in abutting relation.

4. A walking beam, a hinge member attached to one end of the walking beam and having laterally projecting eyes, a walking beam extension having coacting eyes overlapping the eyes on the hinge member, a pintle extending vertically downward 45 through said eyes and permitting lateral swinging movement of the extension, and means for releasably locking the extension in a position of alignment with the body of the beam.

5. A walking beam, a hinge member attached rigidly to one end of the beam and having eyes, an extension having eyes coacting with the first named eyes and overlapping the latter, the hinge member and said extension having opposed laterally projecting lugs abutting against each other when the extension is in alignment with the beam, and detachable means for locking said abutments against each other.

6. A walking beam I-shaped in cross section, a hinge member slotted to embrace the end of the web of the walking beam and having upper and lower flanges bearing against the flanges of the walking beam, said hinge member being riveted thereto, the hinge

member being formed with outwardly projecting eyes and an extension I-shaped in cross section and having eyes formed in its inner end and coacting with the first named eyes, a pintle passing downward through 70 said eyes, the hinge member and the extension having coacting laterally projecting flanges adapted to abut against each other when the extension is in line with the body of the beam and bolts passing through said 75 abutting flanges and holding them in abutting relation.

7. In a walking beam, a hinged nose iron, the nose iron being hinged to the body of the walking beam for lateral swinging movement to thereby provide a clear space for 80 pulling rods and tubing without taking down the beam from its normal working position.

8. In a walking beam, a nose iron constituting a horizontal extension of the walking 85 beam, the nose iron being mounted upon the walking beam for lateral swinging movement in a plane parallel to the axis of the beam whereby to shorten the effective length of the walking beam and to provide a clear 90 space for vertical hoisting action without taking down the beam from its normal position.

In testimony whereof I affix my signature.
